UNITED STATES PATENT OFFICE.

WILLIAM H. BOYER, OF LEBANON, PENNSYLVANIA.

DESIGN FOR A PEN-NIB.

45,286.

Specification for Design. Patented Feb. 24, 1914.

Application filed November 5, 1913. Serial No. 799,405. Term of patent 7 years.

To all whom it may concern:

Be it known that I, WILLIAM H. BOYER, a citizen of the United States, residing at Lebanon, in the county of Lebanon and State of Pennsylvania, have invented a new, original, and ornamental Design for Pen-Nibs, of which the following is a specification, reference being had to the accompanying drawings, forming a part thereof.

Figure 1 is a perspective view of the pen

nib looking at the upper side thereof; and Fig. 2 is a perspective view of the pen nib looking at the lower side thereof.

I claim:

The ornamental design for a pen nib, as shown.

WILLIAM H. BOYER.

Witnesses:

F. A. HOSTEN,
E. EDMONSTON, Jr.
